POCKET TOOTHBRUSH

Roderick E. Asturias, Jr., Redwood City, Calif., assignor
to Twisto Corporation, Redwood City, Calif., a corpora-
tion of California

Application December 6, 1954, Serial No. 33,404

Term of patent 14 years

(Cl. D9—2)

FIG. 1—

FIG. 2—

FIG. 3—

FIG. 4—

FIG. 5—

Figure 1 is a side view of the assembled toothbrush showing my new design;

Figure 2 is an end view of the cover of the device;

Figure 3 is an end view of the toothbrush from the handle end;

Figure 4 is a view of the cover; and

Figure 5 is a view of the toothbrush removed from the cover.

I claim:

The ornamental design for a pocket toothbrush, sub-
stantially as shown and described.
